COMBINATION ANTENNA ROTATOR CONTROL BOX AND PLANTER

Thomas Lee Shelby, New Bremen, Ohio, assignor to Crown
Controls Company, Inc., New Bremen, Ohio, a corpora-
tion of Ohio

Application June 20, 1955, Serial No. 36,604

Term of patent 14 years

(Cl. D26—14)

Fig. 1

Fig. 2

Fig. 3

Fig. 4

Figure 1 is a front perspective view of a combination antenna rotator control box and planter for controlling the direction of an antenna showing my new design;

Figure 2 is an end elevational view;

Figure 3 is a top plan view thereof; and

Figure 4 is a front elevational view thereof.

I claim:

The ornamental design for a combination antenna rotator control box and planter, as shown.
